UNITED STATES PATENT OFFICE.

JOHN D. KELLER, OF SACRAMENTO, CALIFORNIA.

RECIPROCATING PUMP.

1,408,092.

Specification of Letters Patent. Patented Feb. 28, 1922.

Application filed May 11, 1921. Serial No. 468,600.

To all whom it may concern:

Be it known that JOHN D. KELLER, a citizen of the United States, residing at Sacramento, in the county of Sacramento and State of California, has invented new and useful Improvements in Reciprocating Pumps, of which the following is a specification.

This invention relates to a reciprocating pump of the class described in my co-pending application entitled "Pump," bearing Serial No. 417,997, and filed October 19, 1920.

It is a principal object of the present invention to provide a reciprocating pump especially adapted for use in deep wells and which operates a minimum number of moving parts traveling through a short stroke to produce a maximum performance of the pump.

The present invention contemplates the use of a pump cylinder adapted to be longitudinally positioned within the lower end of a well casing, said cylinder carrying pump chambers and passage ways through which water may be forced to circulate by a plurality of simultaneously moving pistons.

The invention is illustrated by way of example in the accompanying drawings in which—

Fig. 1 is a fragmentary view in vertical section, showing the application of my invention to a deep well casing.

Fig. 2 is an enlarged fragmentary view in central vertical section showing the pump with which the present invention is concerned.

Fig. 3 is a view in transverse section through the pump as seen on the line 3—3, Fig. 2.

Fig. 4 is a view in transverse section through the pump as seen on the line 4—4 of Fig. 2.

Referring more particularly to the drawing, 10 indicates a well casing into the lower end of which a pump structure 11 is lowered. This structure comprises an outer cylindrical casing 12 connected at intervals throughout its length by spiders 13, which members 50 carry cylinder head 14. Secured to the opposite sides of the cylinder heads are piston cylinders 15. As shown in Fig. 2 of the drawings, there are three of these cylinders indicated as A, B, and C. The upper end of cylinder A is closed by a head 16 through which a piston rod 17 reciprocates. This

head is designed to form water passage ways 18 and 19 in communication with valve openings 20 and 21 respectively. The gravity operated valves 22 and 23 are mounted over these openings and alternatively seat thereon as the pump operates. The openings 20 are formed through a valve plate 24 which is secured to the member 16 and forms an additional bearing for the 65 shaft 17. The upper end of this plate receives the lower end of a pump casing 25, through which the piston rod 17 extends. The various piston heads 14 are formed with packing glands 26 through which the rod 70 17 passes to receive the lower piston 27. This piston is mounted within the cylinder C. A similar piston 28 is mounted within the cylinder B and connected with the rod 17, while a piston 29 is mounted within the 75 cylinder A and connected with said rod. In order to facilitate in the removal of the pistons and the dismantling of the pump, the piston rod 17 terminates within the upper piston 29, and supplemental rods 17' are 80 successively connected with the other pistons. This also makes it possible to readily increase the capacity of the pump by adding additional units thereto. All of these piston connections are fixed by lock 85 nuts 30. The lower end of cylinder C is fitted with a cylinder head 31, which also forms a part of a valve casing through which liquid may be drawn into the pump structure. This lower casing is formed with 90 separate chambers 32 and 33, and induction ports 34 and 35 respectively. These ports are alternately closed by valve members 36 and 37.

By examining the structure disclosed in 95 the drawings, it will be seen that the upper cylinder head 16, the lower cylinder head 31, the intermediate heads 14, the casing lengths 12, and the piston cylinders, as well as their rods, are assembled to form a pump 100 of desired capacity and are held in their assembled position by stay rods 38. These rods extend down through the casings 12 and are secured to the structure of the upper cylinder head 16 and lower cylinder head 31. 105

By reference to Figs. 3 and 4 it will be noted that the annular passage formed between the piston cylinders 15 and the outer casing 13 are divided into two compartments 39 and 40. These compartments are divided 110 lengthwise by the spiders 13. Each of the spiders is fitted with a pair of circular ports

41 through which communication may be established between the various cylinders and the well casing. Sets of cylinder ports 42 and 43 are formed at the opposite end of 5 the piston cylinders 15 and upon opposite sides of the cylinder.

The operation of the present invention is as follows:

Assuming, for example, that the piston 10 rod 17 is on its downward stroke, any liquid within the various cylinders will be forced outwardly through the lower cylinder ports 42 and into the compartments 39 between the cylinders and the casing. This action will 15 close the lower valve member 37, preventing downward movement of the liquid and will thus force it upwardly through the series of compartments 39 to pass out through the valve opening 21 as the valve member 23 is 20 lifted. When the lower end of the piston stroke has been reached, suitable mechanism will reverse the direction of the movement of the piston rod 17 and will cause the liquid which has been previously been drawn in 25 from the well, through valve opening 34, the vertical passage ways 40 and the ports 43 to be forced out through ports 43. This liquid will then travel upwardly, lifting the valve member 22 and passing out through the well 30 casing, at the same time closing the valve 36. Simultaneously with this action, the pistons will exert a suction stroke to draw liquid in through the cylinders through ports 42 and the valve opening 35. It will thus be evident 35 that alternate reciprocation of the pistons will produce a continuous pumping action.

While I have shown the preferred form of my invention as now known to me, it will 40 be understood that various changes may be made in the construction, combination and arrangement of the parts by those skilled in the art without departing from the spirit of the invention as claimed.

45 What I claim is:

1. In combination with a well casing, a pump adapted to be disposed in an operative position therein, said pump comprising a plurality of cylindrical casing sections substantially fitting within the well casing and disposed in longitudinal alignment; intermediate spiders between the various sections; cylinder heads formed by the center of said spiders; pump cylinders mounted 55 upon the opposite sides of the spiders and in longitudinal alignment; packing glands

formed by the center of said pump heads; a piston rod slidable through said glands; a piston within each of said cylinders and secured to the rod; vertical partition walls disposed diametrically opposite each other and dividing the space between the cylinders and the casing into two vertical passage ways; ports at the tops and bottoms of the cylinders and on opposite sides thereof to 60 separately communicate with the passage-ways; valve casings mounted upon the outer ends of the end cylinders, said casings being formed with two compartments, a compartment of each casing being complementary 70 to the longitudinal passage-ways between the cylinders and their casings; a valve in each of said compartments adapted to alternately open as the pistons are reciprocated; and means for adjustably holding the various cylinders and casings in their assembled positions.

2. In combination with a well casing of a pumping apparatus adapted to be disposed in an operative position adjacent the bottom 80 of the well, the said apparatus comprising a cylindrical exterior casing having an exterior diameter slightly smaller than the inside diameter of the well casing, the said exterior casing formed of a plurality of sections having transverse spiders connecting the same, head members enclosing each of the ends of the pump casing, annular shoulders formed on the head members and the spider members and being materially less in 85 diameter than the exterior casing, pump cylinders sections disposed between the spiders thereby forming a plurality of aligned pump cylinders, the said cylinder sections secured to and aligned by the annular shoulders of 95 the spiders and the heads thus forming a chamber between the cylinder and the casing, pistons reciprocal in the cylinders and a sectional piston rod connecting the pistons and extending upwardly through the well, 100 diametrically opposite and longitudinally extending webs dividing the annular chamber formed between the pump cylinder and the pump casing, a pair of flap valves in each head, one pair being in communication 105 with the other, inlet and discharge apertures formed in opposite ends of the cylinders and each communicating with different head valves, and stay rods and nuts extending longitudinally of the apparatus and uniting 110 and securing the various sections together.

JOHN D. KELLER.
